UNITED STATES PATENT OFFICE

JOSEPH S. DWORSKY, OF NEW YORK, N. Y., ASSIGNOR TO ALBERT PICK-BARTH COMPANY, INC.

DESIGN FOR A REFRIGERATOR LOCK

Application filed July 18, 1930. Serial No. 36,389. Term of patent 14 years.

To all whom it may concern:

Be it known that I, JOSEPH S. DWORSKY, a citizen of the United States, residing at 110 West 86th Street, in the county of New York, State of New York, have invented a new, original, and ornamental Design for a Refrigerator Lock, of which the following is a specification, reference being made to the accompanying drawing, forming a part thereof.

The figure is a front perspective view of a refrigerator lock, showing my new design.

I claim:

The ornamental design for a refrigerator lock as shown.

JOSEPH S. DWORSKY.
